21,380

BRAKE

Ludger E. La Brie, Detroit, Mich., assignor to
Bendix Brake Company, South Bend, Ind., a
corporation of Illinois

Original No. 2,064,617, dated December 15, 1936,
Serial No. 532,265, April 23, 1931. Application
for reissue August 14, 1937, Serial No. 159,116

25 Claims. (Cl. 188—79.5)

This invention relates to brakes, and is illus-
trated as embodied in a novel type of shiftable-
anchorage automobile brake.

One feature of the invention relates to ar-
ranging for fluid-pressure application a brake
of the type having a pair of floating or indi-
vidually-shiftable shoes, i. e., arranged to shift
individually from one anchor to another so that
both shoes have self-energizing characteristics
in both directions of drum rotation. Preferably
there are two fluid-pressure operators adjacent
the opposite ends of the shoes, and these opera-
tors in the forms illustrated in themselves em-
body a number of important features of novelty.
One important object relates to simplifying
the wear adjustment of a brake of this type, by
utilizing adjustable (i. e., expandible) anchors
instead of attempting to adjust the shoes. This
is especially desirable in combination with a
fluid-pressure system of the well-known type,
now practically universal commercially, in which
a light pressure is maintained in the system
even when the brakes are released, as the oper-
ating pistons under the influence of this light
pressure follow the shoes out automatically as the
anchors are adjusted. As this type of system
always includes, in the master cylinder at the
pedal, means for automatically keeping the sys-
tem full of liquid, the adjusted released positions
of the pistons are automatically compensated for
in the master cylinder, and the anchor adjust-
ments are therefore the only adjustments in the
entire system, this not being true of any of the
previously-known arrangements of wear adjust-
ments for brakes of this type.

An important feature of the invention relates
to eliminating shifting of the shoes on forward
application, preferably by using a piston at the
toe of each shoe which is larger in diameter than
the piston at the heel, so that the return springs
will hold the heels of the two shoes continuously
anchored in forward application, although per-
mitting the toes of the shoes to shift into en-
gagement with the anchors on reverse applica-
tion.

Other features relate to a novel duplex me-
chanical applying device capable of being used
as an emergency connection from the usual hand
lever when the above-described fluid-pressure
brakes are used for service, to a simple and
effective automatic adjustment for wear capable
of embodiment in the wheel cylinders, and to
various novel and desirable particular construc-
tions and arrangements which will be apparent
from the following description of the illustrative

embodiments shown in the accompanying draw-
ings, in which:

Figure 1 is a vertical section through a com-
bination mechanical-hydraulic brake of the type
described above, just inside the head of the
brake drum, showing the brake shoes in side
elevation;

Figure 2 is a partial section on the line 2—2
of Figure 1, showing the mechanical or emergency
operating means;

Figure 3 is a section, at right angles to Figure
2, on the line 3—3 of Figure 1, and also showing
the mechanical operating means;

Figure 4 is a section corresponding to Figure 1,
but showing a different brake, and with the
mechanical operating means omitted;

Figures 5 and 6 are sections through the brake
of Figure 4, respectively on the lines 5—5 and
6—6 of Figure 4;

Figure 7 is a section corresponding to Figures 1
and 4, but showing a different brake;

Figures 8 and 9 are sections through the brake
of Figure 7, respectively on the lines 8—8 and
9—9 of Figure 7;

Figure 10 is a section corresponding to Figures 1
1, 4 and 7, but showing a fourth brake;

Figures 11 and 12 are sections through the brake
of Figure 10, respectively on the lines 11—11 and
12—12 of Figure 10;

Figure 13 is a more or less diagrammatic
showing of a complete braking system according
to my invention; and

Figure 14 is a sectional view showing the master
cylinder of Figure 13.

In the brake of Figures 1, 2 and 3, there is a
rotatable drum 10, at the open side of which
is a support such as a novel backing plate 12,
and within which is arranged the brake friction
means which in this case comprises a pair of
floating and individually-shiftable shoes 14 and 40
16. The brake is provided at opposite sides with
a pair of anchorages for the shoe ends, shown
as a pair of anchor posts 18 and 20 carried by
the backing plate and seated in notches in the
ends of the shoes and provided with elongated
retaining washers 22 engaging the sides of the
shoes to hold them laterally (see especially Fig-
ure 3). Return springs 24 are tensioned be-
tween the shoes at their opposite ends.

The brake is applied by novel fluid-pressure
means, which in this embodiment includes a
pair of hydraulic wheel cylinders 26 secured to
the backing plate adjacent each anchorage, and
within each of which is arranged a relatively
large diameter piston 28 acting on the toe of 55

- one of the shoes (i. e., on the part of the shoe which leaves the anchorage during forward braking) and a relatively smaller diameter piston 30 acting on the heel of the other shoe (i. e., on the part of the shoe which remains anchored on forward braking). The pistons may have suitable rubber packing cups 32, shown held by a light spring 34 compressed between them.
- By this arrangement, since the springs 24
- 10 pull equally on the two shoes, and since the larger diameter pistons 28 thrust outwardly with more power than the smaller diameter pistons 30, with any given fluid pressure in the line and in the cylinders 26 between the pistons, the pistons 30
- 15 do not operate to shift the heels of the shoes away from their anchors at any time during forward braking, but merely move far enough to follow the shoes as shoe 14 pivots on anchor 18 and shoe 16 pivots on anchor 20. Thus during forward braking, due to the differential action of the pistons and the equal action of the return springs, the shoes remain continuously anchored instead of leaving the anchors and then coming back with a shock under load.
- 20 During reverse braking, the action is the same until the shoes engage the drum, whereupon the shoes shift to the opposite anchors under the influence of drum friction, the liquid-filled cylinders serving in a manner analogous to door checks to slow up the shifting and minimize shock.
- 25 For emergency application by the usual hand lever, especially when the brakes are on the rear wheels, the brake may have a pair of mechanical applying devices such as floating levers or cams 36 notched out to clear the anchors 18 and 20 and having thrust projections 38 extending at right angles therefrom between the ends of the shoes, the bodies of the levers being arranged
- 30 between the backing plate and the web of shoe 14.
- 35 Levers 36 are operated by means such as a tension element or cable 40 connecting their upper ends and operated by a second cable 42 or the like secured approximately at its center.
- 40 Cable 42 extends at right angles to the brake, through a tubular projection 44 integrally drawn in the backing plate and against the end of which engages and reacts the end of a flexible Bowden-type conduit 46 housing that part of cable 42 which is outside the backing plate.
- 45 In effect the drum 10 and backing plate 12 form a closed brake chamber housing the movable parts, and conduit 46 forms a flexible extension of the brake chamber housing the operating cable 42 or its equivalent. The other end of conduit 46 is in most cases secured to the chassis frame, and the cable 42 issues therefrom and is secured to any desired type of connection from the hand lever.
- 50 The shoes 14 and 16 may be held yieldingly in place by any suitable spring steady rests 48. The pistons are shown acting on the shoes through piston rods 50 rounded at their piston-engaging inner ends and slotted at their outer ends to embrace shoulders formed on the webs of the shoes.
- 55 In the arrangement of Figures 4, 5 and 6, shoes 114 and 116 are operated by the above-described differential diameter pistons 28 and 30, against the resistance of the return springs 24, all as heretofore described. In this case, however, novel anchorages are provided which not only take the torque of the brake but which are also adjustable to compensate for wear of the brake lining. In
- 60 the form illustrated in these particular figures,

the anchors proper are two threaded posts 52 having conical or wedge heads 54 engaged by the conical ends of anchor links 56 pivoted to the ends of the shoes.

Links 56 pass, with sufficient clearance to permit them to shift slightly crosswise with a pivotal action on the anchor heads 54 during application and release of the brake, through sleeves 58 at opposite sides of housings 60 secured to the backing plate and into which the anchor posts 52 are threaded as shown in Figure 5. The tubular central portion of each housing may be closed by a stamping 62. Thus turning the posts 52 operates the wedges 54 to force links 56 slightly apart to take up for wear of the lining on the brake shoes. This is especially advantageous where the cylinders 26 are connected to a hydraulic system of the type, now universally used commercially, in which the fluid in the hydraulic lines is maintained under a light pressure of four or five pounds per square inch, insufficient to overcome springs 24 but sufficient to insure that no air will be sucked into the line. A hydraulic brake system so arranged is disclosed in Figures 13 and 14 wherein is shown a master cylinder 421 having pistons 423 and 425 adapted to be actuated by a pedal 427 to force fluid under brake actuating pressure through conduit 429 to the cylinders 26 to apply the brakes. The pedal is connected to the pistons by pedal link 431. The fluid is maintained under predetermined pressure by a pressure maintenance piston 433 positioned in an auxiliary reservoir 435. Upon the piston 433 a spring 437 bears and with said piston there is associated a spring pressed relief valve 439. The liquid in the system is maintained under a pressure equal to the spring 441 associated with the valve 439.

With this type of fluid pressure operating means, as the anchorages are adjusted to take up for wear, the pistons 28 and 30 are moved automatically outward by the line pressure, following the shoes to their new adjusted positions, and the master cylinder operates automatically, as described in my prior application, to introduce additional fluid into the lines to compensate for the new piston positions. Thus the only adjustments in the entire brake system which must be made by the driver are those at the two anchorages at each brake, and of course it is only necessary to adjust one of these two during any one brake adjustment.

Figures 5 and 6 also show a conduit 66 connecting the two cylinders 26, and a conduit 68 leading to the hydraulic lines on the chassis, which conduits do not appear in Figures 1-3, although of course they are used. Figure 5 also shows one of the removable set screws 70 used in "bleeding" the hydraulic lines.

Figure 10, 11 and 12 show shoes 214 and 216 arranged to anchor slidably at their heel ends against the plane end surfaces of adjustment star wheels 72 formed on adjustable thrust members or plungers 74 threaded into internally threaded pistons 76 having shoulders 78 anchoring against the ends of cylinders 80 mounted on the backing plate and serving as parts of the brake anchorage as well as parts of the applying means.

The toe ends of the shoes are shown provided with separate eccentrically adjustable anchor posts 82 carried by the backing plate and seated when the brake is released in the small ends of pear-shaped openings 84 in the shoe webs. These ends of the shoes are acted on in applying the

brake by plain pistons 86 in cylinders 88, the shoes having rounded thrust ends 88 passed through slots in guides or boots 90 mounted on the cylinders.

It will be seen that adjustment for wear is made at the anchorages by turning the two star wheels 72, the backing plate having openings opposite the star wheels to facilitate the adjustment, the openings having suitable removable covers 92. Pawls 94 of spring steel mounted on the cylinders yieldingly engage the star wheels and hold them in adjusted positions.

Instead of using pistons of different sizes, and to illustrate means partly equivalent to the differential-piston construction in brakes of the type covered by this application, I show in Figure 10 relatively strong return springs 96 tensioned between the heel ends of the shoes and stationary parts such as the cylinders 88 or the backing plate 12, and weaker return springs 98 tensioned between the toe ends of the shoes and the cylinders or backing plate.

Thus in applying the brake, during forward braking the springs 96 hold the heel ends of the shoes continuously anchored through engagement of shoulders 12 with the stationary cylinders, while during reverse braking the shoes open out with the heel ends anchored until the drum friction shifts them to cause the toe ends to anchor on the separate posts 82. During forward braking there is a radially-sliding anchorage permitting the shoes to adjust themselves to the drum, while during reverse braking there is sufficient power without such self-adjustment and the shoes pivot on anchor posts 82. In this construction, as in Figures 4-6, the light line pressures in the hydraulic lines when the brake is released hold the pistons against the shoe ends but cannot overcome springs 96 and 98.

In Figures 7, 8 and 9, the shoes 314 and 316 are actuated by pistons 328 of large diameter and pistons 330 of smaller diameter, all arranged in novel wheel cylinder devices 326 connected by branches 100 from a union 102 fed by the hydraulic line 104. The pistons are provided with suitable rubber packing cups 332, and act with differential pressures, as previously described, against the equal tensions of the return springs 24.

The novel wheel cylinder device 326 contains coaxial cylinders for the two pistons 328 and 330, which cylinders are however separated by a solid wall 106 and provided with separate inlets 108. The inlets 108 are controlled by cone valves 310 having stems loosely but guidingly sliding in passages in plugs 312 threaded into the side of the wheel cylinder device and seated against valve springs 340 which are light enough to be easily overcome by springs 24. The passages containing the valves are in open communication with each other through openings 342, and are also in open communication with conduit 100. The upper valve 310 is shown in brake applied position in Figure 8, and the lower one in brake released position.

In operation, brake applying pressure on the line shifts the valves to the left in Figure 8, and this forces the liquid ahead of the valves into the cylinders below the pistons, the pistons 328 moving first because of their greater area. This causes the brake to be applied in the normal case, the shoes anchoring through engagement of pistons 330 with the wall 106.

If, however, the brake has worn so that it is not fully applied when the valves 310 reach their

left-hand positions, additional liquid can flow past the valves, around their loosely-fitting stems, into the cylinders to cause full application of the brake. When the brake is now again released, valves 310 move to the right for a predetermined distance until they seat, whereupon the additional liquid so introduced is trapped in the cylinders and holds the shoes in automatically adjusted positions with predetermined clearance with respect to the drum. As explained above, the master cylinder at the pedal automatically forces more liquid into the system to replace that trapped in the wheel cylinders. The above-described adjustment introduces the additional liquid behind pistons 328 if it takes place 15 during forward braking, and behind pistons 330 if it takes place during reverse braking.

While several illustrative embodiments have been described in detail, it is not my intention to limit the scope of the invention to those particular embodiments, or otherwise than by the terms of the appended claims. Some features of the present application are dominated by claims in Bendix Patent No. 2,074,717, issued March 23, 1937, and in Dodge Patent No. 2,084,388, issued 20 June 22, 1937, and Sanford Patent No. 2,048,472, issued July 21, 1936, and it is not my intention to claim herein any of the subject-matter of said Bendix and Dodge and Sanford patents. The inventions shown in Figures 1-3 inclusive are 25 also disclosed and are claimed in my copending application 734,249, filed July 9, 1934, and the inventions shown in Figures 13 and 14 are also shown and are claimed in my copending application 499,921, filed December 4, 1930. 30

The inventions shown in Figures 7 to 9 inclusive are also shown and are claimed in my copending application Serial No. 24,388, filed May 31, 1935.

I claim:

1. A brake comprising, in combination with a rotatable drum, a pair of shoes engageable with the drum and each arranged to anchor at one end when the drum is turning in one direction and at its other end when the drum is turning 45 in the other direction, return springs acting on the shoes, a pair of adjustable anchorages one positioned between each pair of adjacent ends of said shoes, and fluid-pressure means for forcing the shoes against the drum to apply the 50 brake and which fluid-pressure means in brake-released position is under a positive pressure less than the force of said springs to cause the fluid-pressure means to expand automatically to compensate for adjustment of the anchorage means 55 but without overcoming the return springs.

2. A brake comprising, in combination with a rotatable drum, a pair of shoes engageable with the drum and each arranged to have one part anchor when the drum is turning in one direction and to have another part anchor when the drum is turning in the other direction, return springs acting on the shoes, a pair of adjustable anchorages each positioned between one pair of adjacent ends of said shoes, fluid-pressure means 60 for forcing the shoes against the drum to apply the brake and additional springs inserted in said fluid pressure means exerting a force to cause the fluid pressure means to expand automatically to compensate for adjustment of the anchorage 65 means but without overcoming the return springs.

3. A brake comprising a pair of shoes, an anchorage for each adjacent pair of shoe ends, each of which anchorages is disconnectedly posi-

- tioned between its adjacent pair of shoe ends to receive anchoring thrust therefrom and each of which anchorages is adjustable to compensate for wear of the shoes, return springs holding the shoes against their anchorages, a fluid-pressure applying device for each adjacent pair of shoe ends, and means for supplying fluid to said fluid pressure applying device in brake released position under a greater pressure than that of the 10 hydrostatic head acting in brake applying direction but less than the brake releasing pressure of said springs.
4. A brake comprising a pair of shoes, an anchorage for each adjacent pair of shoe ends, each of which anchorages is disconnectedly positioned between its adjacent pair of shoe ends to receive anchoring thrust therefrom, return springs holding the shoes against their anchorages, and means comprising a fluid under positive pressure greater than that of the hydrostatic head but less than the brake releasing pressure of the springs, and fluid pressure applying devices maintained by said fluid under pressure in contact with the shoe ends while the 25 shoes are in brake released position.
5. A brake comprising a pair of shoes each individually shiftable to anchor on one end in one direction of rotation of the drum and on the other end in the other direction of rotation 30 of the drum, a pair of cylinders one adjacent each pair of shoe ends, and a pair of pistons in each cylinder and one of which is of greater diameter than the other and which act respectively on said shoes.
- 35 6. A brake comprising a pair of shoes, a pair of cylinders one adjacent each pair of shoe ends, a pair of pistons in each cylinder and one of which is of greater diameter than the other and which act respectively on said shoes, and a pair of anchorages one adjacent each pair of shoe ends.
7. A brake comprising a pair of adjustable wedge means at opposite sides of the brake, and a pair of individually shiftable shoes having 40 parts at their opposite ends engaging said means both for positioning said shoes when the brakes are released and for anchoring the shoes when the brakes are applied, together with a pair of fluid-pressure applying devices acting on said 45 shoes, one adjacent each anchor, each of said fluid pressure applying devices including a pair of piston means held in contact with the shoes both when the brake is being applied and when it is released.
- 50 8. A brake comprising a pair of adjustable wedge anchors at opposite sides of the brake, and a pair of shoes having parts at their opposite ends engaging said anchors, together with a pair of fluid-pressure applying devices acting 55 on said shoes, one adjacent each anchor, each of said applying devices comprising a pair of oppositely acting pistons or the like of different diameters.
- 55 9. A brake having two fluid-pressure applying devices, each comprising a pair of oppositely-acting pistons or the like of different diameters.
10. A brake comprising a pair of floating shoes, a pair of anchors arranged between the opposite ends of the shoes, fluid-pressure applying means, 60 and means embodied in said fluid-pressure means and holding one end of each shoe continuously anchored during forward application and permitting shifting of the shoes to the opposite anchors during reverse application.
- 75 11. A brake comprising a pair of floating shoes, a pair of anchors arranged between the opposite ends of the shoes, return springs acting on the shoes, fluid-pressure applying means also acting on the shoes, means comprising said springs and fluid pressure means for holding one end of each shoe continuously anchored during forward application and for permitting shifting of the shoes to the opposite anchors during reverse application.
12. A hydraulic brake system comprising a 10 pair of shiftable shoes, fluid actuators for the opposite ends of the shoes, means for supplying the actuators with fluid under light pressure even when the brake is released and for supplying them with fluid under increased pressure to apply the brakes, and anchorages for the opposite shoe ends, at least one of which is adjustable to compensate for wear of the shoes, whereby the light pressure causes the actuators to follow up the shoes when the anchorage is adjusted to 15 compensate for said wear.
13. A brake comprising a pair of separated shoes each engageable with the drum, each arranged to anchor at one end when the drum is turning in one direction and at the other end when the drum is turning in the other direction, and each having each end positioned adjacent to but separated from one of the ends of the other, a pair of anchors one positioned between each pair of adjacent shoe ends and with which said ends contact, said anchors being extensible to take up shoe wear and both contacting with both of said shoes independently so that either may be extended to take up shoe wear of both of said shoes and so that the entire brake may 20 be adjusted by the extension of either anchor, and applying devices acting on said shoes, one 25 adjacent each anchor.
14. A brake comprising a pair of separated shoes each having each end positioned adjacent to but separated from one of the ends of the other, a pair of anchors one positioned between each pair of adjacent shoe ends and with which said ends contact, said anchors being extensible to take up shoe wear, and fluid pressure applying 30 devices acting on said shoes, one adjacent each anchor and each of said applying devices comprising a pair of oppositely acting pistons or the like of different diameters.
15. A brake comprising a pair of shiftable 35 anchorage separated shoes each anchoring on one of its ends when applied while the drum is turning in one direction and anchoring on its opposite end when applied while the drum is turning in the opposite direction, means comprising a pair of anchorages one between each pair of adjacent ends of said shoes for both taking the torque of said shoes during braking and for positioning said shoes in their released position, means for adjusting each of said anchorages by 40 a single operation so that both the return position and the anchoring position is adjusted and so that the entire brake may be adjusted by either of said anchorages, and applying devices acting on said shoes, one adjacent each anchor.
16. A brake comprising a pair of individually shiftable shoes, a pair of anchors interposed between the ends of said shoes, springs for maintaining said shoes normally against the anchors, a pair of double diameter cylinders interposed 45 between the ends of said shoes, and a pair of pistons in each cylinder one of which is of greater diameter than the other and both of which exert force against said shoes.
17. A brake comprising a pair of shoes, a pair 50

of anchors interposed between the ends of said shoes, springs for maintaining said shoes normally against the anchors, a pair of double diameter cylinders interposed between the ends of said shoes, and a pair of pistons in each cylinder one of which is of greater diameter than the other and both of which exert force against said shoes whereby said shoes remain with their forward ends against the anchor except in rearward braking.

18. A brake comprising a drum, a backing plate, a pair of brake shoes, a pair of hydraulic cylinders mounted on said backing plate, each adapted to actuate each of said shoes, and resilient means more effective at one end of said shoes than at the other for holding said shoes out of contact with the drum.

19. A brake comprising a drum, a support, a pair of individually shiftable brake shoes in said drum and each arranged to anchor at either end according to the direction of drum rotation, two hydraulic cylinders at opposite sides of the brake each containing two pistons acting respectively on the toe of one shoe and the heel of the other for spreading said shoes apart to cause them to engage the drum, and an element adjustably associated with the piston in each cylinder which acts against one of the shoes and against which the end of said one shoe slidably anchors, the piston in each cylinder associated with the adjustable element having associated therewith means engageable with the end of the cylinder and through which the adjustable element transmits braking torque to the cylinder.

20. A brake comprising a drum, a backing plate, a pair of individually shiftable brake shoes in said drum each shoe being formed with a pear shaped opening, a pair of anchor pins secured to said backing plate and extending respectively through said openings, means for moving said shoes into contact with said drum, and spring means for returning said shoes to released position so arranged that during all brake applications a portion of the rim of each of said openings is retained in contact with its associated anchor pin.

21. A brake comprising a drum, a backing plate, a pair of individually shiftable brake shoes in said drum each shoe being formed adjacent one end with a pear shaped opening, a pair of

anchor pins secured to said backing plate and extending respectively through said openings, means for anchoring the opposite ends of said shoes, means for moving said shoes into contact with said drum, and spring means for returning said shoes to released position so arranged that during forward braking the forward end of each shoe is maintained continuously in anchoring contact with its anchor.

22. In mechanism of the class described, the combination of a drum, a support, a brake shoe arranged to engage with said drum, a fluid motor at each end of said shoe, each said motor acting on said shoe and adapted to move said shoe into engagement with said drum, an anchor for said shoe located adjacent to one of said motors, and a second anchor for said shoe comprising the end of the other motor.

23. A hydraulic brake comprising a drum, a relatively stationary support, a pair of hydraulic motors mounted on said support, a pair of brake shoes, each shoe being acted on by each motor, and resilient means for holding said shoes out of contact with the drum, said means acting more strongly on one end of said shoes than the other.

24. A hydraulic brake comprising a rotatable drum, a support, a pair of hydraulic cylinders mounted on said support, a pair of brake shoes, each shoe being actuated by each cylinder, a pair of anchors for each shoe, a pair of spring means for retracting said shoes, a portion of said spring means exerting a greater force on one shoe than on the other whereby one end of each shoe is pulled from the drum more strongly than the other end.

25. A hydraulic brake system comprising a pair of shiftable shoes, fluid actuators for the opposite ends of the shoes, means for supplying the actuators with fluid under light pressure even when the brake is released and for supplying them with fluid under increased pressure to apply the brakes, and anchorages for the opposite shoe ends, at least one of which is adjustable to compensate for wear of the shoe associated with said anchorage, whereby the light pressure causes the actuator associated with said last mentioned shoe to follow up said shoe when the anchorage is adjusted to compensate for said wear.
